OIL AND GAS WELL CAPPING DEVICE

Gabriel Syobo, Lemoore, Calif.

Application August 22, 1934, Serial No. 741,011

3 Claims. (Cl. 277—63)

The drilling of oil and gas wells is attended by the danger that a high pressure stratum may be encountered from which the oil or gas may issue forth so violently that it cannot be brought under control for some time. The pressure may be run from 1500 to 2500 pounds per square foot or more, in which case before the well can be capped a great quantity of gas, oil, sand, and even rocks will be blown high in the air, endangering all those in the vicinity, damaging the equipment, and leading to great loss of oil and gas.

Various devices have been designed in an effort to control pressures of this kind. My invention is the result of an effort to make a more satisfactory capping device than any that have been known before.

One object of my invention is to provide a capping device of simple massive structure which will assure its capacity to subdue any pressure which may be encountered.

Gas wells are frequently set afire by the striking of a spark in removing the drill. It is accordingly a further object of my invention to provide a capping device having a valve which can be instantly closed to seal the well as soon as the drill rod is removed. For this purpose, the valve is designed to be closed by the force of the fluid itself when started toward closed position.

Another object is to provide a capping device which can remain in position permanently, but with the valve withdrawn from closing position, and which is perfectly tight against leakage.

Another object of the invention is to provide a strong connection between the capping device and the well casing.

I have shown two forms of the invention, by way of example, in the accompanying drawings, wherein

Fig. 1 is a vertical section of one form of capping device designed for relatively small well casings,

Fig. 2 is an elevation of the right side of the capping device shown in Fig. 1,

Fig. 3 is an elevation of the left side of the capping device shown in Fig. 2,

Fig. 4 is a section on the line 4—4 of Fig. 1,

Fig. 5 is a section on the line 5—5 of Fig. 1,

Fig. 6 is a vertical section showing the top of a well casing with the lower end of a capping device connected thereto, this structure being intended for larger size well casings,

Fig. 7 is an elevation of the connections shown in Fig. 6, and

Fig. 8 is a vertical section on an enlarged scale of the valve mechanism shown in Fig. 1.

A valve chamber 11 is provided with an internally threaded inlet nipple 34 and an internally threaded outlet nipple 36. The inlet nipple 34 is of correct size to screw onto the top of the well casing (not shown in Figs. 1-5). One side of the globular body of the valve chamber 11 is cut off on a plane surface 38 and there is attached to this surface by screws 23 a plate 14. Forming an integral part of this plate is a gudgeon 14a, to which is connected by a pin 15 a high pressure check valve 12. In the upper position shown in Fig. 1, the valve 12 rests against a seat 40, while in its lower position shown in dotted lines in Fig. 1, the valve lies in a recess out of line with the bore of the nipples 34 and 36.

For operating the valve 12, a rod 13 is pivotally connected by a pin 17 to a plug 18 which screws into a threaded socket 41 in the center of the valve. A small hole 28a (Fig. 8) may be bored through the valve into the bottom of the socket 41 into which the plug 18 is screwed, to provide an exit for oil and dirt collecting in the bottom of the socket. The outer end of rod 13 extends through a hole 42 in the plate 14, being guided in this hole by a universal joint comprising a ball 25 16 held in a spherical seat 44 by a nut 26, and a bearing sleeve 25 to which the ball 16 is fixed and in which the rod is slidably guided.

In order to hold the valve 12 securely in inoperative position while drilling, a second hole 30 46 is made in plate 14, through which a screw 22 can extend to be screwed into a threaded socket 19 in the valve. A small hole 28 may be bored into the bottom of socket 19, similar to the hole 28a. The hole 42 is surrounded by an externally threaded circular flange 48 to receive a cap 20. The cap can be screwed into position when the valve 12 is closed, or when the rod 13 is removed and the valve is in the dotted line position of Fig. 6. The hole 46 is surrounded by an internally threaded flange 50 adapted to receive a cap 21.

Into the outlet nipple 36 is screwed a second valve chamber 6. This valve chamber contains a valve 9 seating against the upper edge 52 of a sleeve 10 screwed into the valve chamber. The valve 9 is mounted upon a stem 1. The stem has a head 8 resting in a socket in the valve 9 and held therein by a threaded bush 7. The upper end of stem 1 screws into threads in the top sleeve 56 of the valve 6 and has mounted on its upper end a hand wheel 2 held in place between washers 3 by a nut 4. The cylindrical end of stem 1 is guided in aperture 58 of a cup 5, within which packing, (not shown), may be 55

provided. This valve can be assembled by inserting the stem and valve, with hand wheel 2 removed, in through the inlet nipple of the valve before the sleeve 18 is in place, screwing the stem into the sleeve 56, and then screwing home the sleeve 10. The outlet nipple 60 of the valve chamber 6 may be connected to a reservoir or any other place of disposal.

The operation of the device is as follows:

5 The drilling of the well continues until the oil or gas stratum is approached, at which time the drill is disconnected and the capping device is placed in position by screwing the nipple 34 onto the upper end of the well casing. The caps 10 and 21 are removed, the valve 12 is drawn to the dotted line position of Fig. 8, and screw 22 is screwed into socket 10. The valve chamber 6 is removed and the capping device is now in condition for the drilling to continue through it, the path for the drill rod being clear. When 10 the production sand is reached, the drill rod is removed. At the instant the bit emerges from the chamber 11, particularly if it is accompanied by a spray of material from the well, the rod 15 13 is pushed, screw 22 having been previously removed, to throw the valve 12 into the path of fluid passing through the valve chamber. The fluid thereby slams the valve against its seat 40 and effectively seals the well. The closing of 20 the valve can be accomplished so rapidly that even if a fire is started, the attendant can complete the sealing of the well without danger. If the well drillers are not yet ready to connect the well to the reservoir, the caps 20 and 21 can 25 be screwed into place and the well will thus be completely sealed until such time as the work is ready to be continued.

The next step is to screw in the valve chamber 6. This being accomplished, the valve 9 being seated, and the nipple 60 being connected to the reservoir, the device is ready to have the valve 12 opened. This cannot be accomplished by simply pulling out the rod 13, because of the great pressure holding the valve closed. To relieve this pressure, I provide a by-pass 62 connected by bushes 24 to ports 64 and 66 in the plate 14 and valve chamber 6 respectively. The by-pass 62 is provided with a valve 68 and may also have a pressure gauge 70. When the valve 50 68 is opened, fluid is by-passed into the space between valves 9 and 12, eventually establishing the same pressure above the valve as below. This valve will then drop to inoperative position and can be secured in place by screw 22. Then 55 plug 18 on rod 13 is unscrewed from its socket, nut 26 is removed, and the whole valve operating mechanism is taken off. There is then screwed into the socket 41 a large headed screw (not shown), which fits into the seat from which nut 60 26 has been removed. The caps 20 and 21 can now be replaced and the capping device is perfectly tight against leakage. The flow of gas or oil can then be controlled by hand wheel 2. 65 Where the well casing is more than six inches in diameter, I prefer to use a reinforced connection of the capping device to the well casing.

This may be of the kind shown in Figs. 6 and 7. The inlet nipple 11a of the valve chamber is internally threaded to screw onto the casing 31 and is externally threaded to receive a coupling 29. Into the lower half of this coupling there is 5 5 screwed a short pipe section 30. Due to the thickness of the walls of the nipple 11a, the pipe 30 which is to fit into a coupling of a size to screw onto the nipple 11a will be of somewhat larger bore than the outer diameter of the well 10 casing 31. Accordingly the lower end of the pipe section 30 is longitudinally slotted at 14 so that it can be drawn together to embrace the pipe 31 closely. Then the slots 14 are welded and drops of weld metal are inserted in small 15 holes 16 to secure the pipe section 30 to the well casing 31.

This capping device is distinguished by its massive and simple structure which adapts it to withstand the severe conditions to which it is subjected. Its quickness of operation and its 20 25 ability to be tightly sealed are also of great advantage.

Various modifications of the device as shown may be made within the scope of the invention. 25

Having described my invention,

I claim:

1. In an oil or gas well capping device, a valve body comprising aligned inlet and outlet nipples, said inlet nipple having means for connecting the same to the casing head of the well, said valve body having a lateral opening between said nipples completely surrounded by a packing seat lying in a plane substantially parallel to the axis of said nipples, a cover plate covering said opening and packing against said seat, a valve pivotally mounted upon said cover plate by means lying wholly within said valve body, said valve body having a seat within the same adjacent said outlet nipple against which said valve is adapted to seat to close said outlet nipple, said valve being adapted to swing to a position parallel to said cover plate and wholly clear of the space between the openings of said nipples, and a thrust member connected to the face of said valve next to said cover plate, said cover plate having an opening in which said thrust member is tightly guided.

2. The combination claimed in claim 1 having means for swinging said check valve on its pivot comprising a thrust rod pivoted to said check valve and projecting through an opening in said detachable wall plate and a swivel bearing in said opening having a spherically-shaped external portion and a bearing sleeve on the interior thereof for guiding said thrust rod.

3. The combination claimed in claim 1 having means for swinging said check valve on its pivot comprising a thrust rod pivoted to said check valve and projecting through an opening in said detachable wall plate and a swivel bearing in said opening wherein said thrust rod is guided, a cap adapted to fit over said swivelling bearing, and gas-tight connecting means to secure said cap in position.

GABRIEL SYOBO.
